UNITED STATES PATENT OFFICE.

FRANK D. HAGAR, OF BOSTON, MASSACHUSETTS, ASSIGNOR TO HAGAR SHOE MACHINERY COMPANY, OF BOSTON, MASSACHUSETTS, A CORPORATION OF MAINE.

LOOSE-NAILING MACHINE.

SPECIFICATION forming part of Letters Patent No. 755,227, dated March 22, 1904.

Application filed March 14, 1903. Serial No. 147,711. (No model.)

To all whom it may concern:

Be it known that I, FRANK D. HAGAR, a citizen of the United States, and a resident of Boston, county of Suffolk, State of Massachusetts, have invented an Improvement in Loose-Nailing Machines, of which the following description, in connection with the accompanying drawings, is a specification, like letters on the drawings representing like parts.

This invention relates to that type of nail-ing-machines wherein loose nails in bulk are taken from a suitable hopper by means of a raceway and presented singly to a driver to be inserted thereby into the work; and it has for its more particular object the production of novel means for transferring the nails from the lower end of the raceway to the driver-throat, through which the nails pass to and are inserted in the work by or through the operation of the driver.

The various novel features of my invention will be described hereinafter in the subjoined specification and particularly pointed out in the following claims.

Figure 1 is a side elevation of the upper part or head of a nailing-machine with one embodiment of my invention applied thereto. Fig. 2 is front elevation thereof. Fig. 3 is an enlarged horizontal section on the line 3 3, Fig. 1, looking down. Fig. 4 is a similar view on the line 4 4, Fig. 2, but greatly enlarged. Fig. 5 is a partial front elevation of the parts shown in Fig. 4; and Fig. 6 is an enlarged transverse section of the raceway on the line 6 6, Fig. 2, showing a nail in position.

Referring to Figs. 1 and 2, the upper end of a standard or column A is provided with a head A', having bearings for a driver-shaft A², the front end thereof having a disk a fast thereon and provided with a wrist-pin a', connected by a link a² with a cross-head a³, Fig. 2. This cross-head is vertically reciprocable in a suitable guideway a^x in the upturned part A³ of the head and has secured to it a driver d^x. At its rear end the shaft A² is provided with a clutch-pulley C of any desired construction, by means of which the shaft is rotated from a suitable source of power. (Not shown.) The

column A sustains a work support or horn H, which may be of any well-known construction and which forms no part of my present invention. The base of the head is enlarged and extended forward between the driver and the horn to constitute a base-plate, as A⁴, in which the driving-throat is formed, and the nail-transferring means is supported by the base-plate, as will be described. A lateral bracket a⁴, secured to or forming a part of the head, sustains a suitable hopper h to receive the nails in bulk, and this hopper will be provided with lifting devices (not shown) to lift the nails and direct them to the upper end of the raceway R, which leads from the hopper to the top or cover plate A⁵ of the base-plate A⁴.

Referring to Fig. 6, the raceway is shown as substantially rectangular in cross-section, one of its upturned sides r having rigidly secured to its upper edge an inturned cover-plate r', the inner edge thereof being beveled, as at r². The opposite side wall r³ is provided with a cover-plate r⁴, also having its inner edge beveled, as at r⁵; but said plate r⁴ is adjustably held in place by screws 3, passed through slots in the plate and into the side wall r³, whereby the slot-like opening between the beveled edges r² and r⁵ can be varied in width to accommodate nails having shanks of different thickness. At its lower end the raceway is beveled to rest upon the plate A⁵, with the slot-like opening in the top of the raceway registering with a curved slot a¹² in the plate A⁵. The base-plate A⁴ has a circular recess a¹³ in its upper face, Figs. 3, 4, and 5, in which is located the transfrerer, shown as a toothed disk or wheel t, secured to an upright rotatable stud t^x, extended through the plate A⁵ and having attached to it a ratchet m. The slot a¹² is concentric with the teeth t' of the transfrerer from the lower end of the raceway to the driving-throat t²⁰ in the base-plate A⁴ and its cover-plate and located directly beneath the driver d^x, the slot-like passage in the raceway being in a plane substantially tangent to the pitch-line of the transfrerer-teeth. Said teeth are separated enough to receive the shank of the largest nail which may

be used with the apparatus, while the heads of the nails rest upon the plate A⁵, their shanks passing through the slot a¹² and between the teeth t'. As the transerrer is rotated step by step, as will be described, the nails leave the lower end of the raceway and are taken one by one by the toothed transerrer and moved forward toward the throat t²⁰, which is formed at the end of the slot a¹². A slide-pawl m', held in engagement with the ratchet by a spring s, Fig. 3, is connected by a ball-and-socket joint m², Figs. 1 and 3, with the lower end of a lever m³, fulcrumed at m⁴ on the head, the upper end of said lever having a roll m⁴ in engagement with a cam M on the driver-shaft A². (See Fig. 1.) At each revolution of said shaft the lever m³ is oscillated to reciprocate the pawl back and forth, and by its engagement with the ratchet m the transerrer t is rotated step by step, each advance movement thereof presenting a nail to the throat to be driven and receiving one from the raceway. A detent-pawl m⁵, Fig. 3, prevents retrogression of the ratchet and transerrer.

The nails slide by gravity down the raceway from the hopper to the lower end thereof and are there picked off one by one by the toothed transerrer t. In order to adapt the machine to nails having heads of different sizes, I have made the throat t²⁰ adjustable, and to this end the front half of the throat is formed in a throat-plate t²¹, the edges of which are beveled to fit in undercut sides or guideways t²², made in the plate A⁵, the throat-plate being moved outward to enlarge the throat. A set-screw 30, extended transversely from the edge of the plate A⁵, bears against one side of the throat-plate and tightly clamps it in adjusted position. By this device I can drive nails having different sizes of heads and even hob-nails, the throat being adjusted to the size of the head of the nail to be used.

In order to avoid widening the transferring-slot a¹² when the throat is enlarged, I have cut away the top of the throat-plate at the side of the throat opposite the slot to receive a sliding plate p, having slots p' therein, Figs. 3 and 4, to receive clamping-screws 25, which enter the throat-plate beneath. The rear edge of the plate p is curved, as at p⁵, to form the outer side wall of the slot a¹², so that by moving the plate in when the throat-plate is moved out the width of the slot is maintained constant, as desired, irrespective of the size of the throat t²⁰. By thus maintaining the width of the transferring-slot uniform I can use any size of nail so long as its head is wide enough to rest upon the tops of the side walls of the transferring-slot, the width of the latter being great enough to take in the shanks of maximum thickness.

The machine herein described can be run at high speed. The nails are transferred posi-

tively and accurately to driving position, and various kinds of loose nailing can be performed with a very extended range in the size, shape, and character of the nails employed.

Having described my invention, what I claim, and desire to secure by Letters Patent, is—

1. In an apparatus of the class described, a hopper for the nails, a raceway to convey the nails therefrom, a reciprocating driver, a plate having a throat through which the nails are driven into the work and provided with a curved transferring-slot leading from the lower end of the raceway to the throat, the width of said slot up to the throat being less than the width of a nail-head, a rotatable, peripherally-toothed transerrer adapted to engage the shanks of the nails below said plate and transfer them from the raceway to the throat, the heads of the nails resting upon the top of the slotted plate at each side of the slot and their shanks depending through the latter, and means to reciprocate the transerrer step by step.

2. In an apparatus of the class described, a reciprocating driver, a plate having a throat through which the nails are driven into the work, said plate having a circularly-curved slot leading to the throat, a transerrer rotatably mounted beneath the slotted plate and having a toothed periphery concentric with said slot, a raceway to deliver nails to the outer end of the slot, the transerrer engaging the shanks of and taking the nails one by one from the raceway and moving them through the slot to the throat, and the nail-heads resting upon the top of the slotted plate, and means, including a ratchet axially secured to the transerrer, and a co-operating pawl, to advance the transerrer one tooth for each reciprocation of the driver.

3. In an apparatus of the class described, a reciprocating driver, a plate having a throat in the driver-path and a nail-transferring slot leading thereto, means to vary the size of the throat to permit the use of nails having heads of different sizes, a raceway to deliver nails to the outer end of the slot, a rotatable, peripherally-toothed transerrer to engage the shanks of the nails below the slot and move them therethrough from the raceway to the throat, and means to rotate said transerrer step by step.

4. In an apparatus of the class described, a reciprocating driver, a plate having a throat in the driver-path and a nail-transferring slot leading thereto, a throat-plate having one side of the throat formed therein, means to adjust the throat-plate in or out, to vary the size of the throat, and an independently-adjustable plate forming a portion of the outer wall of the transferring-slot, whereby the width of the latter may be maintained constant irrespective of the size of the throat.

5. In an apparatus of the class described, a reciprocating driver, a base-plate having a throat-opening therein and a circular recess in its upper face, a toothed transferrer rotatably mounted in said recess, a cover-plate for the base-plate, having a transferring-slot concentric with the transferrer, to sustain the nails with their shanks depending between the teeth of the transferrer, said cover-plate having one side of a driving-throat formed therein, and means adjustably mounted on the cover-plate to complete the throat and vary the size thereof to accommodate nails having heads of different sizes.
- 15 6. In an apparatus of the class described, a rotatable driver-shaft, a reciprocating driver operatively connected therewith, a base-plate having an adjustable throat in the driver-path,
- a raceway, a rotatable, toothed transferrer to convey the nails from the raceway to the 20 throat, a ratchet axially secured to the transferrer, a sliding pawl to coöperate with and actuate the pawl and advance the transferrer step by step, a rocking lever connected at one end by a ball-and-socket joint with the pawl, 25 and a cam on the driver-shaft in operative engagement with the other end of the lever, to rock the same in accordance with the reciprocations of the driver.

In testimony whereof I have signed my name 30 to this specification in the presence of two subscribing witnesses.
